RIFLE

George J. Hyde, Dayton, Ohio, assignor to Firearms Research Corporation, New York, N. Y., a corporation of New York

Original application August 9, 1940, Serial No. 351,949. Divided and this application September 15, 1942, Serial No. 458,371

2 Claims. (Cl. 42—16)

My invention relates to rifles, particularly of the semi-automatic type, i. e., rifles which may be controlled either for single shot firing or for repeating firing.

This application is a division of my copending application Serial No. 351,949, filed August 9, 1940, for "Rifle," on which Letters Patent No. 2,342,283, dated February 22, 1944, have issued.

In accordance with a prominent aspect of the invention, the rifle consists of only two assemblies which may readily be attached to or detached from each other; more particularly, one of these assemblies is a trigger assembly which is so constructed that, when detached from the other assembly, the parts thereof remain in proper operative relation with respect to each other.

In accordance with another prominent aspect of the invention, the aforesaid trigger assembly, when removed from the other assembly, exposes those parts of the latter which most frequently require a cleaning operation.

My invention relates particularly to a rifle which, aside from the grips and stock, entirely avoids the use of assembling screws or bolts.

My invention has further reference to novel features embodied in the rifle bolt and in the cocking bar.

Various other objects and advantages of my invention will become apparent from the following detailed description.

My invention relates to the rifle, features and combinations of the character hereinafter described and claimed.

For an understanding of my invention and for an illustration of one of the forms thereof, reference is to be had to the accompanying drawings, in which:

Fig. 1 is a vertical sectional view, partly in elevation, showing the rifle of the invention, this view being taken on the line 1—1 of Fig. 2 looking in the direction of the arrows;

Fig. 2 is a horizontal sectional view, partly in plan, taken substantially on the line 2—2 of Fig. 1 looking in the direction of the arrows;

Fig. 3 is a transverse, vertical sectional view, taken on the line 3—3 of Fig. 2 looking in the direction of the arrows;

Fig. 4 is a perspective view, with parts disassembled, showing the ejecting means for the spent shells;

Fig. 5 is a horizontal sectional view, partly in plan, taken substantially on the line 5—5 of Fig. 1 looking in the direction of the arrows;

Fig. 6 is a vertical sectional view, partly in ele-

vation, taken on the line 6—6 of Fig. 5 looking in the direction of the arrows;

Fig. 7 is a vertical sectional view, corresponding generally with Fig. 6, and showing some of the parts in different positions; and

Fig. 8 is a side elevational view, with parts disassembled, showing the rifle of this invention.

Referring to the drawings, the rifle herein illustrated comprises, in general, a barrel 1, a forward grip 2, a rear grip 3, a housing 4 comprising a forward block 5, a stock 6 and a magazine 7. The block 5 at the forward end thereof, comprises an internally threaded passage 8 into which the rear end of the barrel 1 is threaded.

The forward grip 2 is secured in a suitable manner to a stem 9, Fig. 1, carried by the forward end of said housing block 5 and the rear grip 3 is bolted or otherwise suitably secured to a trigger casing 10 utilizable as hereinafter described. The stock 6 is secured to the rear wall 4a of the housing 4 by a screw bolt 11d. The magazine 7 is adapted to be detachably associated with the housing block 5.

The housing 4 comprises a top wall 4b and side walls 4c, 4c serving to form a chamber C utilizable as hereinafter described. The housing 4 further comprises the aforesaid rear wall 4a to which the stock 6 is secured, the interior surface of this rear wall 4a being provided with a recess 4d of substantially rectangular configuration, Figs. 1 and 2.

The aforesaid housing walls 4b, 4c and 4c, at the front end of the housing 4, merge into the block 5 which comprises an approximately vertical wall 11 facing the chamber C, the lower section of this wall being inclined and provided with a horizontal slot 11a, as shown in Fig. 1. The block 5 comprises a vertical chamber C1 merging into a horizontal bolt-receiving passage 40 P aligned with the bore of the barrel 1, said passage P having an orifice or passage O opening laterally and upwardly therefrom.

The aforesaid trigger casing 10, at the end thereof toward the right (Fig. 1) comprises a vertical flange 12 adapted to fit snugly within the aforesaid recess 4d of the housing 4. The end of the trigger casing 10 toward the left, Fig. 1, comprises a recess in which is received an oscillatory member 13 having a latching member 13a cooperable with the aforesaid slot 11a, the member 13 carrying an exterior handle 14 having an inner lug 14a adapted to seat in a corresponding recess in the adjacent casing surface. Further, as shown in Fig. 1, that face of the trigger casing 10 toward the left is inclined as indicated at 15

in correspondence with the inclination of the wall 11.

With the trigger casing 10 positioned as shown in Fig. 1, the handle 14 may be operated to move the latching member 13a out of the slot 11a whereupon said casing 10 may be swung generally in a counter-clockwise direction (Fig. 1) about the shoulder 4e bounding the lower part of the recess 4d and then moved bodily to remove the flange 12 therefrom from the recess 4d. At this time, as shown in Fig. 8, the trigger casing constitutes an assembly entirely separate and removed from the housing 4.

In as simple a manner, the trigger casing 10 may be reassembled with the housing 4. To this end, the lower part of the flange 12 is seated on the shoulder 4e whereupon said trigger casing 10 is moved to closed position, the walls 15 and 11 coming into binding engagement at this time. The handle 14 is then swung to move the latching member 13a into the slot 11a to thereby positively lock the trigger casing 10 in its operative position.

The hereinbefore described flange 12, when positioned as shown in Fig. 1, has secured thereto a member 16 horizontally extending into the chamber C and having a helical spring 17 disposed thereon in freely movable relation, the last coil of the spring 17 toward the right (Fig. 1) preferably having smaller diameter than the other spring coils so as to detachably anchor that end of said spring 17 toward the right in the position shown.

Mounted for slidable movement in the chamber C is the bolt 18 comprising a base section 18a having on each lower side surface thereof a horizontal groove 19, these grooves 19 receiving, respectively, the inwardly facing tracks 20 formed at the upper part of the trigger casing 10, Fig. 3. As shown in Fig. 1, the bolt base section 18a is provided with a horizontal passage 18b in which the helical spring 17 and its supporting member 16 is freely received.

As illustrated in Fig. 1, the lower surface of the bolt base section 18a comprises a cam surface 18c utilizable as hereinafter described.

The bolt 18 comprises an actuating section 18d projecting forwardly from the base section 18a, said bolt actuating section 18d being aligned with the passage P and the bore of the barrel 1. At its far end, the bolt actuating section 18d comprises a tubular wall 18e forming a chamber in which is disposed a firing pin 21c formed integrally with and disposed centrally of said actuating section 18d.

The bolt actuating section 18d, on its exterior surface, comprises a longitudinally extending groove 18f which receives the spent shell extractor member 21. At its end toward the left (Fig. 2) the extractor member 21 comprises the usual flanged tip 21a adapted to engage the inner rim surface of the spent shell as well understood in the art. The groove 18f may increase in taper from left to right (Fig. 2) and the extractor member 21 may be of similar configuration whereby the latter may be assembled in the groove by a driving fit between adjacent surfaces.

In addition to the foregoing, the bolt actuating section 18d, on its exterior surface more or less opposite the groove 18f, comprises a longitudinally extending groove 18g utilizable as hereinafter described.

Referring to Figs. 1, 2 and 3, one side of the bolt base section 18a is provided with a longitudinally extending groove which receives the cock-

ing bar 22 having, at that end thereof toward the left, an inwardly extending section 22a adapted to engage a shouldered surface 18h of said bolt base section 18a. The cocking bar 22 is biased from right to left (Fig. 2) by a helical spring 23 secured at 24 to said cocking bar 22 and at 25 to the adjacent side wall 4c of the housing 4. Secured to the cocking bar 22 and extending transversely therefrom is a transverse pin 26, Fig. 2, extending through a slot 4f formed longitudinally in said last named side wall 4c, the pin 26, exteriorly of the latter, carrying an actuating knob 27.

The bottom wall surface of the hereinbefore described trigger casing 10 is shaped to form a trigger guard 30 in which the rifle trigger is mounted for oscillatory movement. This trigger comprises a finger piece 31 depending from an intermediate trigger section 32 having projecting from opposite respective sides thereof the horizontally aligned lugs 33 seating in bearing surfaces formed, respectively, in the lower side walls 10a of the trigger casing 10 (Fig. 7).

Upstanding from the intermediate trigger section 32 is a finger 34 engaged by the end of a leaf spring element 35a formed integrally with a base 35 (Fig. 5) having projecting therefrom the other leaf spring elements 35b, 35c and 35d utilizable as hereinafter described, and the spring base 35 being seated in a recess 10b formed interiorly of the trigger casing 10 (Fig. 5). As shown in Figs. 6 and 7, a plate 95, seated as hereinafter described holds the spring base 35 in its recess 10b.

The spring element 35a aforesaid biases the trigger in a clockwise direction (Fig. 1), such movement of the trigger being limited by engagement of the aforesaid trigger finger 34 and the trigger finger 31 hereinafter referred to with the respective members 10c upstanding in the casing 10 and formed integrally therewith (Fig. 5).

In addition to the above noted finger 34, a finger 31 (Figs. 5 and 6) upstands from the intermediate trigger section 32, this finger 31 being provided with a longitudinally extending slot 38 which receives the shank of a sear-controlling member 39 (Fig. 7), the member 39 having a link 40 pivoted thereto at 41 (Figs. 6 and 7), the trigger finger 31 coacting with the free end of said link 40, as shown in Figs. 6 and 7.

The above described leaf spring element 35c (Figs. 6 and 7) engages the link 40 to bias it toward the trigger finger 31, the effect of this spring biasing the sear-controlling member 39 from left to right (Figs. 5, 6 and 7).

As shown in Figs. 6 and 7, the sear-controlling member 39, at the left of the link 40, comprises a section 39a having inclined surfaces 39b, 39c utilizable as hereinafter described. The sear-controlling member 39, at the right of the link 40, comprises an upstanding block 39d which coacts either with a holding surface 41a of a sear 41 or is disposed in a recess 41b formed in the lower surface of said sear 41.

The sear 41 is supported pivot-fashioned at 41c in a bearing surface 10d transversely formed in the trigger casing 10. The sear 41, toward the right, (Figs. 6 and 7) comprises a horizontal section 41d, the lower surface of which is engaged and continuously biased upwardly by the free end of a leaf spring element 42a having a base 42 from which projects a normally curved leaf spring element 42b utilizable as hereinafter described, the spring base 42 being seated in a recess 10e formed interiorly of the trigger casing

10, said spring base 42 being held in said recess 10e in the manner hereinafter referred to.

As shown in Figs. 1, 6 and 7, the sear 41, on the upper surface thereof comprises an inclined surface 41e with which, during operation of the rifle, the hereinbefore described cam surface 18c of the bolt 18 coacts.

As shown in Fig. 5, the trigger casing 10 comprises an upstanding, transverse wall 10f having a pair of spaced longitudinal slots 10g and 10h, the shank of the above described sear-controlling member 39 being freely slideable in the slot 10g.

Slidable in the slot 10h of the wall 10f is the shank of a sear-controlling member 43 having at the end thereof toward the right (Fig. 5) an upstanding block 43a which, the same as the block 39d, is adapted to coact either with the sear surface 41a or be seated in the recess 41b thereof. Disposed in longitudinal alinement with the slot 10h and formed on the interior surface of the casing 10 is a slot 10i which freely receives the shank end of the sear-controlling member 43 toward the left (Fig. 5), this shank, at its extreme end toward the left (Fig. 5) comprising an actuating knob 43b. The aforesaid leaf spring element 35b has an angular section coactable with a similar angular section of the sear-controlling member 43 to bias the same from right to left (Fig. 5).

Referring to Figs. 1, 6 and 7, the trigger casing 10 is shown as comprising a transversely disposed, horizontal seat 10j in which is rotatably received the shaft 45 of a safety lever having an actuating handle 45a disposed exteriorly of said casing 10 (Fig. 5). The shaft 45 adjacent the handle 45a comprises a circumferential groove 45b having two flat sections 45c, 45d formed therein. Beyond the groove 45b, the shaft 45 comprises a flat section 45e connected circumferentially by a curved section 45f.

The end of the hereinbefore described leaf spring section 42b (Fig. 5) rides in the aforesaid groove 45b and coacts alternately with the flat sections 45c, 45d thereof to retain the shaft 45 in either of the positions shown in Figs. 6 and 7. When the shaft 45 is in the position shown in Fig. 6, the curved section 45f of said shaft 45 coacts with a downwardly extending nose 41f of the sear 41 to hold the sear 41 elevated. At this time, the leaf spring element 42b engages the flat section 45c of the groove 45b (Fig. 1). When the shaft 45 is in the position shown in Fig. 7, the flat section 45e of said shaft 45 is disposed opposite the sear nose 41f whereby the sear 41 may be depressed, by the bolt 18, against the action of the leaf spring element 42a in the manner hereinafter described. At this time, the leaf spring element 42b engages the flat section 45d of the groove 45b.

Referring further to Figs. 1, 6 and 7, the trigger casing 10 is shown as comprising a transversely disposed, horizontal seat 10k in which is rotatably received the shaft 46 of a selector lever having an actuating handle 46a disposed exteriorly of said casing 10 (Fig. 5). The shaft 46 adjacent the handle 46a comprises a circumferential groove 46b having two flat sections 46c, 46d formed therein. Beyond the groove 46b, the shaft 46 comprises two flat sections 46e, 46f angularly related to each other on the same peripheral section of said shaft 46.

The end of the hereinbefore described leaf spring section 35d (Fig. 1) rides in the aforesaid groove 46b and coacts alternately with the flat sections 46c, 46d to retain the shaft 46 in either of the two positions shown in Figs. 6 and 7.

When the shaft 46 is in the position shown in Fig. 6, the flat section 46e of said shaft 46 is disposed opposite and removed from the path of the inclined section 39c of the sear-controlling member 39. At this time, the leaf spring element 35d is in engagement with the flat section 46c of the groove 46b (Fig. 1). When the shaft 46 is in the position shown in Fig. 7, the flat section 46f of said shaft 46 is disposed in the path of the inclined section 39c of the sear-controlling member 39. At this time, the leaf spring element 35d is in engagement with the flat section 46d of the groove 46b.

Referring to Figs. 2, 3 and 4, the wall defining one side of the bolt-receiving passage P in the block 5 is shown as comprising a horizontal opening 70, the wall surface of which forms a bearing for an ejector comprising a member 71 mounted therein for oscillatory movement, the member 71, exteriorly of the block 5, carrying an actuating handle 72 formed from spring steel and comprising a locking tip 72a adapted to be releasably seated in a recess 73 formed in the outer surface of the block 5.

As illustrated in Fig. 3, the member 71, interiorly of the passage P, comprises an angular extension 71a adapted to be received by the hereinbefore described groove 18g during movement of the bolt 18.

As clearly shown in Fig. 4, the aforesaid opening 70 has a recess 74 communicating therewith at one side thereof, an undercut slot 75 extending from this recess partly around the opening 70. The member 71 comprises a lateral extension 71b, the configuration of which corresponds with that of the recess 74. In view of the foregoing, it will be understood that the ejector member 71 may be moved longitudinally through the opening 70, the extension 71b being received by the recess 74. Thereafter, during oscillation of the handle 72, the ejector is retained in its intended position by action of the walls of the slot 75 on the extension 71b of the member 71. Obviously, the ejector may be removed from its seat in as simple a manner, it being necessary first to line up the extension 71b with the recess 74.

The hereinbefore described spring base 42 was described as seating in a recess 10e of the trigger casing 10. In accordance with the invention, the recess 10e tapers to a slight extent longitudinally of the trigger casing 10, the spring 42 being tapered in a corresponding manner. Accordingly, the spring base may be associated with its recess in a driving-fit relation whereby said spring base is securely retained in its intended position without requiring the use of screws or pins.

Referring to Figs. 6 and 7, a plate 95 is shown as forming an upper closure for that part of the trigger casing toward the left. The recess 10m of the trigger casing 10 for the plate 95 tapers to a slight extent longitudinally of the trigger casing 10 and plate 95 is similarly tapered. Therefore, the plate 95 may be associated with its seating recess in driving-fit relation to thereby positively anchor the same in position. However, before the plate 95 is thus seated, the base comprising the spring elements 35a, 35b, 35c and 35d is seated in its proper position. Thereupon, the plate 95 is seated in position as described, this plate serving said spring arrangement in its seat.

As shown in Fig. 3, the trigger casing 10 comprises, at opposite sides thereof, the outer, upstanding walls 10n which, when said trigger casing 10 is in assembled relation, are disposed in close-fitting, side-by-side relation with respect to

the lower surfaces of the walls **4c**, **4c** of the housing **4**. This is desirable because it prevents entry of foreign matter interiorly of the rifle at the junction between the trigger casing **10** and the main assembly comprising the chamber **4**, the barrel and the stock **6**.

In accordance with the invention, the arrangement is such that the leaf spring elements of the spring structure comprising the base **35**, when seated in position, serve, respectively, (1) as the biasing means for and the means for holding the trigger in its seat, (2) as the biasing means for and the means for holding the sear-controlling member **43** in its seat, (3) as the biasing means for and the means for holding the sear-controlling member **39** in its seat, and (4) as the means for holding the selector lever **46**, **46a** in its seat and for holding it in either of its adjusted positions.

Further in accordance with the invention, the arrangement is such that the leaf spring elements of the spring structure comprising the base **42**, when seated in position, serve (1) as the biasing means for holding the sear **41** in its seat, and (2) as the means for holding the safety lever **45**, **45a** in its seat and for holding it in either of its adjusted positions.

Accordingly, in view of the foregoing, it follows that all of the operating parts of the trigger assembly are retained in their respective seats without the use of pins or screws. Further, when the trigger assembly is detached from the main assembly as hereinbefore described, all of the operating parts of the trigger assembly remain in their intended positions without any change whatsoever. In other words, the main assembly is without function as regards the maintenance of any of the parts of the trigger assembly in their respective seats.

With the sear **41** in elevated position, the rifle is maintained cocked by reason of the fact that the inclined sear surface **41e** is in locking engagement with the cam surface **18c** of the bolt **18** to hold the latter in its position toward the right (Fig. 1), the spring **17** being under firing compression at this time. Further, at this time, the sear-controlling member **39** is in its position toward the right (Fig. 6) wherein the block section **39d** thereof is beneath the sear-holding surface **41a** to hold the sear **41** elevated, the sear-controlling member **43** being in its position toward the left (Fig. 5) wherein the block section **43a** thereof is disposed beneath the sear recess **41b**.

For single-shot firing, the shaft **46** is positioned, as shown in Fig. 7, so that the flat surface **46f** thereof is disposed in the path of the sear-controlling member **39** to maintain the same in tilted relation somewhat as shown. Accordingly, under the conditions recited, when the trigger is pulled, the sear-controlling member **39** is moved toward the left against the action of the spring element **35c** (Fig. 6) wherein the block section **39d** thereof is disengaged from the sear-holding surface **41a**. As a result, the weight of the bolt **18** depresses the sear **41** against the action of the spring element **42a**. When this happens, the bolt **18**, under the influence of the compressed spring **17**, moves suddenly from right to left (Fig. 1), the bolt extension **18d** at the left (Fig. 1) engaging the rear of that cartridge **S** disposed uppermost in the magazine **7** and moving said cartridge **S** along the sloping surface **p** of the head **5**. Immediately thereafter, the bolt seats the cartridge **S** in firing position with the advanced edge of the cartridge shell seated against the flange **1a**

of the barrel **1** and, when the cartridge is thus positioned, the firing pin **21c** engages the cartridge detonator to fire the cartridge.

When the cartridge **S** became seated in firing position, as described above, the rear end of the cartridge **S** was seated in the chamber defined by the tubular wall **18e** with the flanged tip **21a** in gripping relation with the rim of the shell **S**.

Responsive to the firing act, the bolt **18** recoils and the groove **18g** of the bolt **18** moves rearwardly, the ejector extension **71a** being in this groove during this movement thereof. As the groove **18g** moves to the right, as viewed in Fig. 2, the ejector extension **71a** engages the rim of the spent shell **S** and removes it from the bolt, the extracted shell **S** inherently turning and engaging the curved face **o** of the orifice **O** under substantial impact whereby said spent shell **S** is thrown forwardly in the general direction of the barrel of the gun. After the spent shell **S** has been ejected, the recoil of the bolt **18**, under the influence of the firing shot, continues until the cam surface **18c** has moved somewhat to the right of the inclined sear section **41e** (Fig. 1) whereby the sear **41** moves to its elevated position under the influence of the spring section **42a**.

When the trigger was pulled, as described above, the sear-controlling member **39** was moved to the position shown in Fig. 7 and it thereby assumed a somewhat greater tilted relation by reason of the fact that the inclined section **39c** thereof rode upwardly along the flat section **46f** of the shaft **46**. Accordingly, when the sear **41** moves to its upper position, as last described, the sear recess **41b** rises from the block section **39d** and, thereupon, the sear-controlling member **39** moves to the right (Fig. 7) under the influence of the spring section **35c** until said block section **39** passes beneath the sear-holding surface **41a** to hold the sear **41** elevated. This happens before the cam surface **18c** of the bolt **18** returns from its excursion to the right as described above and, when said cam surface **18c** does return to the sear **41**, the latter has been elevated as described to thereby, at its inclined surface **41e**, engage the bolt cam surface **18c** and hold the bolt in position, with the spring **17** under compression, ready for the next shot, this occurring when the trigger is pulled again.

Ordinarily, the trigger is in its drawn position when the recoil of the bolt **18** causes the cam surface **18c** thereof to move somewhat to the right of the inclined sear section **41e**, as last described. However, the trigger is ineffective to prevent the described movement of the sear-controlling member **39** toward the right (Fig. 7) by reason of the fact that said sear-controlling member **39** is tilted at this time as shown in Fig. 7. Because thus tilted, the link **40** assumes the position shown in Fig. 7, wherein the curved concave surface **40a** thereof, rather than its nose **40b**, is in engagement with the nose of the trigger. Therefore, under the influence of the spring section **35c**, the sear-controlling member **39** moves toward the right, as described above, the link **40** moving counter-clockwise (Fig. 7) to accommodate such movement.

For continuous shot firing, the shaft **46** is moved to the position shown in Fig. 6 wherein the flat section **46e** thereof is positioned upwardly. Accordingly, no tilting movement of the sear-controlling member **39** occurs and, when the trigger is pulled, the link nose **40b**, rather than the link concave surface **40a**, is engaged by the nose of the trigger. The link nose **40b** is so shaped that

it is not readily disengaged from the trigger nose during continuous firing. Furthermore, during continuous firing, the inclined surface 39b of the member 39 is locked under the inclined casing surface 10s to thereby positively prevent upward movement of said member 39. Accordingly, after the shot is fired, with the shaft 46 positioned as described above, movement of the sear-controlling member 39 toward the right (Fig. 6) is prevented by the trigger and, therefore, the sear 41 does not become effective to lock the bolt 18 in its rear position. It results, therefore, that with said shaft 46 positioned as last described, continuous firing of the rifle occurs until the last cartridge is fired.

When the shaft 45 is positioned, as shown in Fig. 7, the rifle is in shooting condition. At this time, the flat section 45e of said shaft 45 faces the nose 41f of the sear 41. Therefore, the sear may move between the positions described above to lock and release the bolt.

When the shaft 45 is positioned as shown in Fig. 6, the rifle is in "safety" position by reason of the fact that the curved surface 45f of said shaft 45 coacts with the sear nose 41f to hold the sear 41 elevated. When thus elevated, the bolt 18 may not be moved to firing position.

The cocking bar 22 is used to manually cock the rifle whenever that operation becomes necessary. As will be noted, the spring 23 continuously maintains the cocking bar 22 in its forward position except when manually restrained.

While the invention has been described with respect to a certain particular preferred example

which gives satisfactory results, it will be understood by those skilled in the art after understanding the invention, that various changes and modifications may be made without departing from the spirit and scope of the invention and it is intended, therefore, in the appended claims to cover all such changes and modifications.

What is claimed is:

- 5 1. In a rifle having a housing provided therein with a chamber that is open at the bottom thereof, the combination therewith of a firing mechanism assembly including a casing having inwardly extending tracks at the top and opposite sides thereof, a reciprocatory rifle bolt supported by said casing and having longitudinal grooves in opposite sides thereof to receive said tracks, and means for detachably securing said assembly as a unit to said housing in the open end of said chamber.
- 10 2. In a rifle having a housing provided therein with a chamber, the combination therewith of a firing mechanism assembly including a casing, a rifle bolt supported by said casing for reciprocation in said chamber, means on said casing and engaged with said bolt for guiding the latter during reciprocation thereof, a sear on said casing for holding said rifle bolt in cocked position, and means for detachably securing said assembly as a unit to said housing, the various operating parts of the assembly remaining, respectively, in their normal operative positions and the rifle bolt remaining in cocked position after detachment of said unit from said housing.
